UNITED STATES PATENT OFFICE.

HARRY H. GARRISON, OF WILKESBARRE, PENNSYLVANIA, ASSIGNOR OF ONE-HALF TO HARRY G. SHUPP, OF WILKESBARRE, PENNSYLVANIA.

SHOW-CARD.

SPECIFICATION forming part of Letters Patent No. 731,884, dated June 23, 1903.

Application filed November 22, 1902. Serial No. 132,469. (No model.)

To all whom it may concern:

Be it known that I, HARRY H. GARRISON, a citizen of the United States, residing at Wilkesbarre, in the county of Luzerne and State of Pennsylvania, have invented new and useful Improvements in Show-Cards, of which the following is a specification.

My invention relates to an improved device or show-card for the purpose of exhibiting loose diamonds or other precious stones without mounting them for window display or for exhibiting to customers, whereby the precious stones will remain in the position in which they are placed and can be readily removed for examination or rearranged in any desired design.

My invention pertains to the arranging and the holding of precious stones for exhibition purposes through the medium of a non-hardening and non-cementing material, such as wax or its equivalent.

In the accompanying drawings I illustrate one way in which my invention may be utilized, though it will be readily understood that in a broad sense it may be utilized in other ways for the purpose of receiving and holding precious stones for exhibition purposes without mounting in a manner which enables them to be quickly attached and detached for examination purposes and without any injury whatever to the stones.

Figure 1 is a perspective view of my invention applied to a show-card, the same being supported in an inclined position for window or case exhibition purposes. Fig. 2 is a transverse sectional view of the same.

In the use of my invention the precious stones *a* are held detachably in their adjusted position through the intervention of wax or its equivalent which is practically non-hardening and non-cementing, but through a frictional contact and suction action will hold the stones in their position when they are placed upon the wax and given a slight pressure to force their projections slightly therein.

In the drawings the wax *b* is arranged between two layers of cardboard *c* and *f*. These two cardboards are glued together around their openings by means of suitable glue or other cement *h*.

The outer layer of cardboard *c* will prefer-

ably be provided with perforations *i* over its surface to expose through the perforations the layers of wax placed between the two layers of cardboard. These perforations are of a size sufficient to permit the projecting portions of the stones to be forced into the exposed portions of the wax. The wax then serves to hold the stones in position by a combined wedging and suction action, and the cards can be handled without disturbing the positions of the stones, and the stones can be readily removed for examination by a customer. When the stones are removed, the wax will not adhere to the stone in any sense and leaves it free to be carefully and thoroughly examined and will not disturb the luster or brilliancy thereof.

While I here show the outer cardboard arranged with perforations over its surface, thus permitting considerable latitude in the arranging of the stones in certain designs, yet it will be readily understood that the wax could be wholly exposed and the stones arranged thereon in any desirable design, or the outer cardboard may have perforations cut therein in the design of a crescent, sunburst, or any other design.

I am aware that heretofore precious and other stones have been supported for exhibition purposes by means of glue or other cement; but it will be readily understood that in this relation the stones cannot be detached and readily rearranged in any desired design for the purpose of illustration to a customer. It will also be readily understood that in the use of cement or glue should the stones be removed for the purpose of exhibiting to a customer a certain portion of the cement or glue will adhere thereto, making it necessary to either remove the glue, with a possible injury to the stone, or to examine the stone in the hands of a probable purchaser with the glue or cement thereon. Where, however, a non-hardening and non-cementing material, such as wax, is used, whereby the stone is held in position by a frictional and suctional action, the stones can be readily arranged and rearranged for the purpose of exhibition to a customer and readily and quickly attached and detached from its supporting-surface without any of the objections heretofore mentioned where

glue and cement is used. Where glue and cement is used, a permanent attachment of the stones is made, and the stones cannot be detached without segregating the means of attachment. This means of attachment by a permanent connection such as cement or glue, is therefore entirely different from my means of support and attachment, which is of a detachable character and enables the stone to be readily and immediately attached and detached at any desired point upon the holding-surface.

Having thus described my invention, what I claim, and desire to secure by Letters Patent, is—

1. A show-card consisting of a backing carrying a layer of non-hardening and non-cementing material.
2. A show-card consisting of a backing carrying a layer of non-hardening and non-cementing material and a front card carried by the backing and covering a portion of said non-hardening and non-cementing material.
3. A show-card consisting of a backing carrying a layer of non-hardening and non-cementing material, and a front cardboard attached to the backing, the front cardboard having a plurality of perforations to expose through the perforations the layer of non-hardening and non-cementing material.

4. A show-card consisting of a backing carrying a layer of non-hardening and non-cementing material and a front card cemented to the edges of the backing, and covering a portion of the non-hardening and non-cementing material.

5. A show-card consisting of a backing carrying a layer of non-hardening and non-cementing material, the front card cemented to the edges of the backing, the front card having a plurality of perforations to expose through the perforations the layer of non-hardening and non-cementing material.

In testimony whereof I have hereunto set my hand in the presence of two subscribing witnesses.

HARRY H. GARRISON.
